UNITED STATES PATENT OFFICE.

STEPHEN MOLTRUP, OF BEAVER FALLS, PENNSYLVANIA.

METALLIC POST.

No. 821,725.

Specification of Letters Patent.

Patented May 29, 1906.

Application filed November 30, 1904. Renewed November 2, 1905. Serial No. 285,609.

To all whom it may concern:

Be it known that I, STEPHEN MOLTRUP, of Beaver Falls, Beaver county, Pennsylvania, have invented a new and useful Metallic Post, of which the following is a full, clear, and exact description, reference being had to the accompanying drawings, forming part of this specification, in which—

Figure 1 is a side elevation showing a preferred form of my metallic post. Fig. 2 is a partial vertical section of the same, and Fig. 3 is a cross-section on the line III III of Fig. 2.

My invention relates to the class of hollow metallic posts or poles, and is designed to provide a simple structure which may be easily and cheaply made and which will give great resistance against lateral strains.

In the drawings I show a post having a tapering body which is substantially circular in cross-section and formed of two outer tapering spirally-wound flat steel strips 2 and two inner tapering spirally-wound flat steel strips 3, which are wound in the opposite direction—that is, two strips are wound in a right-hand spiral and the other strips wound in a left-hand spiral, so that the spirals cross each other, preferably at each convolution. The outer spirals are wound of slightly greater diameter than the inner spirals, and between them are placed the vertically-extending flat strips 4. I have shown the vertical strips as four in number, though they may be of any desired number. The several strips are secured together by rivets 5, and the vertical strips are preferably positioned at the crossings of the spiral strips, so that a single rivet secures the three thicknesses firmly together at each crossing-point. By positioning the vertical strips at the crossing-points of the spirals I thus provide a simple and strong structure which will present great resistance to lateral strains of pressure. The top and bottom finish of the post or pole may be of any desired form. I have shown an ornamental top cap 6 in the form of a hollow casting with the ends of the spirals and the ends of the vertical strips riveted through it at 7, as shown in Fig. 2. I also preferably

provide a base consisting of a pipe-casting 8, having a reduced upper portion 9, which extends upwardly within the lower portion of the hollow skeleton body. The lower ends of the spirals and vertical strips may be riveted at their crossing-points to a ring 10, which is forced over a shoulder on the base

portion between the lower portion and the upper reduced portion.

The advantages of my invention result from the use of the flat strips wound in opposite spirals and riveted together at the crossing-points and, further, from the use of the flat vertical strips which are riveted to the spirals, preferably at their crossing-points. The vertical strips may be placed outside or inside the spiral structure instead of between the spiral strips, though I prefer the form shown, and the number of both the spiral strips and the vertical strips, as well as their arrangement, may be varied without departing from my invention.

I claim—

1. A post or column comprising metal strips wound in right and left hand helices, and members extending in alinement with the intersections of said strips, and connected therewith at said intersections; substantially as described.

2. A post or column comprising metal strips wound in right and left hand tapering helices, and members extending in alinement with the intersection of said strips, and connected therewith at said intersections; substantially as described.

3. A post or column comprising metal strips wound in right and left hand helices, having substantially equal pitch, and members extending in alinement with the intersections of said strips, and connected therewith at said intersections; substantially as described.

4. A post or column comprising metal strips wound in right and left hand tapering helices, having substantially equal pitch, and members extending in alinement with the intersections of said strips, and connected therewith at said intersections; substantially as described.

5. A post or column comprising metal strips wound in right and left hand helices, having substantially equal pitch, and members extending between said strips in alinement with the intersections thereof and riveted thereto at each intersection; substantially as described.

In testimony whereof I have hereunto set my hand.

STEPHEN MOLTRUP.
